UNITED STATES PATENT OFFICE.

IVAN WEISKOPF, OF MORCHENSTERN, AUSTRIA-HUNGARY.

DEVICE FOR SPINNING GLASS.

946,179.

Specification of Letters Patent. Patented Jan. 11, 1910.

Application filed April 14, 1909. Serial No. 489,779.

To all whom it may concern:

Be it known that I, IVAN WEISKOPF, doctor of medicine, manufacturer, a subject of the Emperor of Austria-Hungary, and a 5 resident of Morchenstern, Bohemia, in the Empire of Austria-Hungary, have invented a Device for Spinning Glass; and I do hereby declare the following to be a full, clear, and exact description of the invention, such 10 as will enable others skilled in the art to which it appertains to make and use the same.

The subject-matter of the present invention is a device for spinning glass for the 15 purpose of producing so-called glass wool or glass threads or filaments for optional purposes, but particularly for insulating purposes.

The improved device according to the invention differs from the known device for spinning glass, which consists in the end of a glass rod being exposed to an open jet of flame produced at the blowing table, by the rod of glass resting with its end in a fire- 20 proof hollow body, a so-called fusing point, open in front and exposed to the flame, toward which the rod of glass is fed forward automatically in proportion to the diminution of the melted glass mass which is drawn 25 away in filamentary form.

In order that the invention may be clearly understood reference will be made to the accompanying drawing in which one constructional form of such a device is represented by way of example, and in which:

Figure 1 is a longitudinal section through the device, and Fig. 2 is an end elevation partly in section of the same, whereas Fig. 3 shows part of the device as shown in Fig. 40 1 on a larger scale, and Figs. 4 and 5 are details in sectional elevation explained here- after.

Similar reference characters denote like parts in all views.

Referring to the drawing, the device consists of a table 1, on which stands or pillars 2, 3 adjustable in height are arranged which serve for supporting a number of chutes 4 arranged beside one another, in each of 45 which one or more thin glass rods 5 are placed. The rear stands 3 have vertically adjustable hooked extensible members 6 and the front stands 2 a plate 7 provided with suitable incisions for the chutes and like-

wise adjustable vertically. In front of the 55 stands 2 is arranged beside one another a number of supports or stands 8 which carry the hollow body or fusing point 9. The fusing point is, generally speaking, a fire- proof hollow body open in front and at the 60 rear, into which the end of the glass rod enters up to a stop or shoulder in the hollow body. According to the form represented, the hollow body 9 has the shape of a cylinder which is provided at its rear end with 65 flanges 10 and possesses at its front end one or more laterally arranged holes 11. When one hole only is provided, it may be located exactly in the axis of the body and be of optional shape, for example that of a slot 70 or small round hole. Figs. 4 and 5 respectively clearly show the arrangement of a small hole 11 at the point and laterally in the conical end of the fusing point 9. The fusing point itself is attached to the sup- 75 port 8 by a covering member 12 provided with a hole through it and firmly screwed to the support. The flame, which has heretofore acted directly on the end of the glass rod, is now directed against the fusing 80 point. For this a burner tube 13 is used which, like a Bunsen burner, receives air from the pipe 14 and gas from the pipe 15. In order to obtain an intense heat at that 85 place at which the glass filament of thread is drawn away from the fused glass, i. e. at the hole 11, a blowpipe flame is directed against this place by means of the burner 16; the latter is fed with gas and air from the pipes 14 and 15, as clearly shown. As 90 the present arrangement readily enables a number of fusing devices to be placed beside one another, several fusing points 9 are provided beside one another, in each of which a glass rod, guided in a chute, enters with 95 its end and against which the flames of the two burner tubes 13, 16 act. It is to be noted that the pipes 14, 15 open into common pipes 17, 18 and the burner tubes 16 into a common pipe 19. The device is completed by a vertically adjustable guard or protecting plate 20 which is arranged in such manner at the end of each fusing point that the flame from the burners 13 cannot be directed toward the glass threads or 100 filaments, as the same would otherwise become melted down. Further, a protecting box or casing 21 is provided which incloses 105

the essential parts around the fusing point and is likewise for preventing the flames changing their position owing to drafts of air.

5 The device works as follows: After the glass rods 5 are placed in the chutes and are inserted so far into the fusing point that they abut against the latter with their front ends, they are loaded with weights 22. The 10 flames from the burners 13 heat the fusing points near their free ends, whereas the blowpipe flames from the burners 16 directly contact with the glass at the melting place. When a drop of glass is visible, the 15 operator touches it with a small rod having a glass point directed through the opening 23 of the box 21, withdraws the same quickly, and throws it in the manner usual heretofore onto a rapidly rotating drum on which the 20 glass filament is wound up.

The advantages of the described means are manifold. They consist in the possibility of arranging an optional number of the means beside one another, whereby the output which is possible for one workman is considerably increased. The most important, however, is the employment of a fusing point, whereby a small harbor, so to say, is provided for the fusing glass, by which the 25 temperature can be gradually increased up to the melting point of the glass, and dropping of the glass and breaking of the filament or thread caused thereby are prevented.

It may be mentioned that the glass spinning process can be carried into practice not 30 only together with the two flames 13, 16, but also with the one or other flame alone, without departing from the spirit and scope of the invention.

40 What I claim as my invention and desire to secure by Letters Patent is:

1. In a device for use when spinning glass, the combination of a table, a refractory hollow body or fusing point open at the rear 45 and in front and carried on said table, a burner on said table for heating said body, and means for automatically feeding a glass rod into said body in proportion as fused glass is removed therefrom, substantially as 50 described.

2. In a device for use when spinning glass, the combination, with a table, of a chute mounted adjustably thereon, a refractory hollow body or fusing point open in front 55 and at the rear mounted on said table in front of and in line with said chute, and a burner attached to said table for heating said body, substantially as described.

3. In a device for use when spinning glass, 60 the combination, with a table, of a chute mounted adjustably and slanting thereon, a refractory hollow body or fusing point open in front and at the rear mounted slantwise on said table in front of and in line with 65 said chute, and a burner attached to said

table for sending a flame through the opening in the front of said body, substantially as described.

4. In a device for use when spinning glass, the combination, with a table, of a chute mounted adjustably thereon, a refractory hollow body or fusing point open in front and at the rear mounted on said table in front of and in line with said chute, a burner attached to said table for heating said body, and another burner attached to said table for sending a flame through the opening in the front of said body, substantially as described. 70 75

5. In a device for use when spinning glass, the combination, with a table, of a chute mounted adjustably and slanting thereon, a refractory cylindrical flanged hollow body or fusing point open at the rear and having a lateral hole at its front end, said body being supported by means of the flange slantwise on said table in front of and in line with said chute, and a burner attached to said table for heating said body, substantially as described. 80 85

6. In a device for use when spinning glass, the combination, with a table, of a chute mounted adjustably and slanting thereon, a refractory hollow body or fusing point open in front and at the rear mounted 95 slantwise on said table in front of and in line with said chute, a burner attached to said table for heating said body, and a guard arranged on the table at the front end of the hollow body, substantially as described. 100

7. In a device for use when spinning glass, the combination, with a table, of a chute mounted adjustably thereon, a refractory hollow body or fusing point open in front 105 and at the rear mounted on said table in front of and in line with said chute, a burner attached to said table for heating said body, and a vertically adjustable guard arranged on the table at the front end of the hollow 110 body, substantially as described.

8. In a device for use when spinning glass, the combination, with a table, of a chute mounted adjustably and slanting thereon, a refractory hollow body or fusing point open 115 in front and at the rear mounted slantwise on said table in front of and in line with said chute, a burner attached to said table for heating said body, another burner attached to said table for sending a flame 120 through the opening in the front of said body, and a box on the table inclosing said body and the space immediately in front of said burners, for withholding drafts from the flames of the burners, substantially as 125 described.

9. In a device for use when spinning glass, the combination, with a table, of a chute mounted adjustably and slanting thereon, a refractory hollow body or fusing point 130

open in front and at the rear mounted slant-wise on said table in front of and in line with said chute, a burner attached to said table for heating said body, and a weight 5 slidable in said channel for automatically feeding a glass rod into said body in proportion as fused glass is removed therefrom, substantially as described.

10. In means for use when spinning glass, 10 a cylindrical, refractory, hollow fusing

point flanged at the rear and having a conical front end provided with a small lateral hole therein, substantially as described.

In testimony whereof I have signed my name to this specification in the presence of 15 two subscribing witnesses.

IVAN WEISKOPF.
